UNITED STATES PATENT OFFICE.

JAMES T. SMITH, OF NEWARK, NEW JERSEY.

LEATHER-PRESS.

1,344,214.

Specification of Letters Patent. Patented June 22, 1920.

Application filed October 9, 1919. Serial No. 329,574.

To all whom it may concern:

Be it known that I, JAMES T. SMITH, a citizen of the United States, and a resident of Newark, in the county of Essex and State 5 of New Jersey, have invented new and useful Improvements in Leather-Presses, of which the following is a specification.

This invention relates to that type of presses which are used in the manufacture 10 of leather for pressing it in the last stages of its manufacture, either to flatten it out smooth, called smooth plating, or to emboss upon its finished surface an artificial grain, it being understood that very great pressure 15 with the application of some heat to the leather is required for doing this. Obviously the effective surface of the press is small as compared to the size of the leather and for this reason difficulty has been experienced in avoiding marks on the leather from the overlapping of successive impressions, and also it has been difficult to dispose of or handle the large portion of leather which was not on the bed of the press, without 20 endangering the operator's hands. Presses heretofore have had a cast iron or rigid head held down by rods anchored to a base, such rods being arranged close to the bed and allowing only a very restricted 25 space for the portions of leather which are not on the bed, and for manipulating the same. It has been customary to roll up the leather, leaving only a side portion of about 30 the width of the press bed, and then when this has been pressed by shifting it along the bed of the press it is rolled up and another portion unrolled. It is very difficult 35 to manipulate these rolls of leather and at the same time keep the unrolled portion smooth on the bed of the press, and in the effort 40 to do this the operator's hands are frequently caught in the press. A great deal of time is lost and the work of pressing the leather greatly retarded by so shifting 45 the leather and manipulating the rolls, even when done with safety, and the quantity of product is thus limited. Another difficulty 50 in pressing the leather heretofore has been that there has been no way of measuring the amount of pressure, and the operator sometimes uses too great pressure before he realizes it and damages the leather.

The objects of the present invention are to secure a leather press in which ample space is provided for the portions of the leather

which are not upon the bed of the press; to thus avoid the necessity for rolling up the marginal portions of the leather and unrolling them as the leather is shifted upon the bed of the press; to relieve the operator of 60 this work of rolling and necessity for holding the rolls with his hands; to thus leave his hands free to smooth out and adjust the leather upon the bed of the press; to secure an improved product, in which the pressing 65 is more perfectly done without lap-marks and the like; to secure a pressure which will yield beyond a certain point; to thus avoid marking or damaging the leather; to utilize for the purpose of securing a yielding pressure, a head formed of material which will slightly spring under pressure from the bed of the press; to utilize this yielding for 70 measuring the amount of pressure; and to obtain other advantages and results as may 75 be brought out in the following description.

Referring to the accompanying drawings, in which like numerals of reference indicate the same parts throughout the several views,

Figure 1 is a side elevation of a press of 80 my improved construction, showing the platform and table in section, and

Fig. 2 is a cross-sectional view of the same on line 2-2, Fig. 1.

In the specific embodiment of the invention shown in said drawings, 1 indicates a suitable base, which in this instance I have shown composed of heavy I-beams 2, 2, and provided at its opposite ends with uprights 3, 3 which carry a top piece 4 to the under 85 side of which the head 5 of the press is secured, said head being steam-heated in any usual and well-known manner (not shown) so as to better impress the leather forced against it as hereinafter described. The said 90 uprights 3, 3 may be of any suitable form or construction, but I have shown them as each an I-beam supported at its lower end by bolting to the base I-beams 2, 2 and braced by braces 6, 6 extending laterally outward 100 to the ends of an angle iron 7 arranged transversely of the base. Suitable corner braces 8, 8 are also bolted one at each end of the base 1 and also to the adjusted up- 105 right 3.

Midway of the uprights 3, 3 and at a considerable distance therefrom a vertical guideway 9 is mounted upon the base 1, and in said guideway is mounted a sliding bed 10 adapted to coöperate with the head 5 to 110

press the leather, said guideway being of any suitable construction commonly employed in presses and said sliding bed being adapted to be reciprocated vertically by 5 any suitable and well-known means, such as the toggles 11, 11 adapted to be forced apart by the up-stroke of a cam roller 12 having end bearings in guide blocks 13 in vertical slots 14, said roller being actuated 10 by a cam or eccentric 15 turned by power through any suitable mechanism under the control of the operator. The bed 10 has at its edges and substantially flush with its top an extension 16 which has its outer margin- 15 al portions 17 curved downwardly, as shown, so that the top of the bed and the extension together form a large table to receive the leather, considerably larger than the leather gripping portion of the press, 20 and thus the leather is supported and held out flat for a much larger extent of itself than the portion actually pressed at one time. This enables the leather to simply lie over the table, fully extended, and be 25 easily and readily shifted by the operators as required to bring different portions of it successively between the bed 10 and head 5 of the press. This saves a great deal of time and enables the output of the machine 30 to be increased fifty per cent. The product is also superior, and the operators do not run any risk of injury.

The uprights 3, 3 are spaced far apart, at 35 the ends of the base 1, not only to give room for the leather to hang over the table but also to provide a long top-piece 4 which can spring or bend slightly on such a curvature as will not disturb the parallelism of the head 5 at the middle of said top-piece to the 40 bed 10, the said top piece 4, base 2 and uprights 3 forming a polysided head supporting frame. This insures a pressure for the leather which is somewhat resilient and will not mark the leather if some portions are 45 thicker than others or where the edges of pressed portions overlap, although it will be understood that this resiliency is very slight and does not prevent the leather receiving a pressure of three hundred pounds 50 or more to the square inch. The resiliency is furthermore utilized for measuring the pressure exerted, as by connecting the movable member of a measuring device to the middle of the beam or top piece 4 and fulcrumed upon a stationary or fixed support. 55 I have shown this done in the drawings by mounting a bar 19 upon the uprights 3, 3 by means of brackets 20, 20 so that said bar lies parallel to the beam or top piece 4 at the 60 front side of the press and does not partake of the up and down springing of the beam or top piece. A lever 21 is fulcrumed upon this bar 19 as at 22, and pivotally connected intermediate its ends to the beam by a 65 shackle 23 so that as the beam springs up

and down the free end of the lever will move correspondingly. Then by connecting said free end of the lever to a gage 24, which I have also shown mounted upon the bar 19 the pressure can be read by the operator as the leather is pressed, and he can know whether or not it is all right. Any other suitable means for transmitting the movement of the top piece 4 to a pressure-indicating device might be used instead of the one which I have shown and described. 75

While I have shown the invention as embodied in a leather smooth plating or embossing machine, it will be understood that the invention is equally well adapted for 80 use in other types of presses, or in connection with the manufacture of other materials.

Various modifications and changes may be made in manufacturing my improved machine by those skilled in the art without departing from the spirit and scope of the invention, and I do not wish to be understood as restricting myself except as required by the following claims when construed in the light of the prior art. 85

Having thus described the invention, what I claim is:

1. In a press of the character described, the combination of a polysided frame, a 95 head mounted upon one side thereof, a movable bed mounted upon that side of said frame opposite the said head to coöperate therewith, said bed being spaced from all sides of said frame and free from all sides thereof except that side upon which it is mounted, so that the work being operated upon can be slid over the bed and those portions of the work not immediately on the bed depend over the edges thereof into an 100 out-of-the-way position.

2. In a press of the character described, the combination of a polysided frame, a head mounted upon one side thereof, a bed mounted within said frame and spaced from all sides thereof, guide means to coöperate with said bed mounted upon that side of the frame opposite said head and spaced from all other sides of said frame, and means arranged between said guide means within 110 said frame for actuating said bed toward and from said head.

3. In a press of the character described, the combination of a base, uprights mounted upon opposite ends of said base, a top piece arranged between the said uprights and supported thereby, a head mounted upon said top piece and spaced from the ends thereof, a bed mounted between said base and said head to coöperate therewith and spaced from said base, top piece, and uprights, spaced guide members to receive said bed between them projecting inwardly from said base and spaced and free from said top piece and uprights, and means arranged be- 115 120 125 130

- tween said guide members for actuating said bed toward and from said head.
4. In a press, the combination with a movable bed, guide means for said bed, and actuating means for moving said bed in said guide means, of a head supporting frame comprising a base to support said bed guide means and actuating means, uprights on said base spaced and free from said bed, 10 guide means and actuating means, a top piece mounted on said uprights and extending between the same, and a head mounted upon said top piece and spaced from said uprights.
- 15 5. In a press of the character described, the combination of a polysided frame, a head mounted upon one side thereof, a bed mounted within said frame and spaced from all sides thereof, guide means for said bed 20 mounted upon that side of the frame opposite said head and spaced and free from all sides thereof except that side upon which said guide means is mounted, and an extension for said bed forming therewith a table substantially flush with the working face of 25 said bed so as to receive the work being operated upon by the press and facilitate its application and removal to and from the said bed.
- 30 6. In a press of the character described, the combination of a polysided frame, a head mounted upon one side thereof, a bed mounted within said frame and spaced from all sides thereof, guide means for said bed 35 mounted upon that side of the frame opposite said head and spaced and free from all sides thereof except that side upon which said guide means is mounted, and an extension for said bed forming therewith a table 40 substantially flush with the working face of said bed, said table being spaced from all sides of said frame so as to receive the work being operated upon by the press and facilitate its application and removal to and from 45 the said bed, the work as it has been operated upon by the press sliding over the said table and depending from the sides thereof.
7. In a press of the character described, the combination of a polysided frame, a 50 head mounted upon one side thereof, a bed mounted within said frame and spaced from all sides thereof, guide means for said bed mounted upon that side of the frame opposite said head and spaced and free from all 55 sides thereof except that side upon which said guide means is mounted, said guide means being arranged between said bed and the said side of the frame upon which the guide means is mounted so that the work 60 can be slid over the bed and those portions of the work not immediately upon the work-
- ing face of the bed depend over the edges of the bed into an out-of-the-way position.
8. In a press of the character described, the combination of a frame having an elongated top piece of spring material, a head fixed on said top piece and spaced from the ends thereof, and a reciprocating bed to co-operate with said head, said top piece yielding under pressure upon said head without 65 destroying the parallelism of said head and bed.
9. In a press of the character described, the combination of a frame including a rigid base, uprights mounted thereon, a top 70 piece formed of spring material mounted upon said uprights and extending between the same, a head on said top piece and spaced from the ends thereof and said uprights, and a reciprocating bed mounted on 75 said base to co-operate with said head, said top piece yielding under pressure upon said head without destroying the parallelism of 80 said head and bed.
10. In a press of the character described, a bed, means for reciprocating said bed, a head opposite said bed, and a top piece carrying said head and enough longer than it to yield or spring under pressure without 85 destroying the parallelism of said head to the bed.
11. In a press of the character described, a bed, means for reciprocating said bed, a head opposite said bed, a top piece carrying said head and enough longer than it to yield 90 or spring under pressure, and pressure measuring means arranged and adapted to be operated by such movement of the top piece.
12. In a press of the character described, a bed, means for reciprocating said bed, a head opposite said bed, a top piece carrying said head and enough longer than it to yield or spring under pressure, a fixed support, a member engaging said fixed support and the 100 top piece, and pressure indicating means connected to said member.
13. In a press of the character described, a bed, means for reciprocating said bed, a head opposite said bed, uprights at the opposite ends of the head and bed and spaced therefrom, a top piece mounted on said uprights and carrying said head, said top piece being enough longer than the head to 105 spring under pressure, a bar parallel to said top piece and secured at its opposite ends to said uprights, a member engaging said bar and top piece, a lever pivotally engaging said bar and top piece, and pressure indicating means connected to said lever.

JAMES T. SMITH,
